Primary Examiner — Barbara Fox*Assistant Examiner* — Messina L Smith(74) *Attorney, Agent, or Firm* — IpHorgan Ltd.(57) **CLAIM**

The ornamental design for a rice milling machine, as shown and described.

DESCRIPTION

FIG. 1 is a perspective view of a rice milling machine showing the new design;

FIG. 2 is a front view thereof;

FIG. 3 is a rear view thereof;

FIG. 4 is a left side view thereof;

FIG. 5 is a right side view thereof;

FIG. 6 is top plan view thereof; and,

FIG. 7 is bottom plan view thereof.

The portion of the machine shown in broken lines in FIG. 1 shows an interior part of the machine that forms no part of the claimed design.

1 Claim, 7 Drawing Sheets(56)
